DESIGN FOR A COMBINATION MECHANICAL
PENCIL AND KNIFE

Jacob M. Weiss, New York, N. Y.

Application February 14, 1948, Serial No. 144,507

Term of patent 14 years

(Cl. D74—24)

To all whom it may concern:

Be it known that I, Jacob M. Weiss, a citizen of the United States of America and a resident of the city of New York, in the county of Kings and State of New York, have invented a new, original, and ornamental Design for a Combination Mechanical Pencil and Knife, of which the following is a specification, reference being had to the accompanying drawing, forming a part thereof.

Fig. 1 is an enlarged side view of a combination mechanical pencil and knife, showing my new design,

Fig. 2 is an enlarged front elevational view of the sleeve portion only; and

Fig. 3 is an enlarged side view of the pencil and knife removed from the sleeve shown in Fig. 2.

The essential features of my design reside in the parts shown in full lines.

I claim:

The ornamental design for a combination mechanical pencil and knife, substantially as shown and described.

JACOB M. WEISS.
